CIGARETTE CASE

Filed Sept. 27, 1929

UNITED STATES PATENT OFFICE

WILLIAM C. HIERING, OF NEWARK, NEW JERSEY, ASSIGNOR TO J. E. MERGOTT COMPANY, OF NEWARK, NEW JERSEY, A CORPORATION OF DELAWARE

CIGARETTE CASE

Application filed September 27, 1929. Serial No. 395,486.

This invention relates to a cigarette case by means of which cigarettes may be carried in the usual paper packages in which they are sold.

5 The standard brands of cigarettes are at present vended in paper packages of substantially uniform size and shape, which are such as to enable the packages to be conveniently carried in the pockets of clothing or in 10 women's handbags. The cigarettes are tightly packed into the paper packages by machines, and in order to extract a cigarette, it is usually necessary to jar the package by 15 shaking to loosen the cigarettes. This practice is objectionable as the jarring of the package also loosens the tobacco in the cigarettes. Also, when carried in a pocket, the paper packages are of insufficient strength to 20 protect the cigarettes from breakage or crushing.

It is an object of this invention to provide a case in which a paper package of cigarettes may be placed to protect the cigarettes from breaking and crushing.

25 A further object is the provision of a cigarette package holding case having a two-part cover adapted to open the length of the top of a package of cigarettes, to expose the entire contents of the package and enable the cigarettes to be conveniently extracted therefrom.

These and other objects are attained by the novel construction, combination and arrangement of parts hereinafter described 35 and shown in the accompanying drawings constituting a material part of this disclosure and in which:

Figure 1 represents a perspective view showing the package holding case in a closed 40 condition.

Figure 2 represents a partial cross-sectional elevational view of the case.

Figure 3 represents a perspective view of the upper portion of the case when the latter 45 is in an open condition.

Referring to the drawings, the cigarette package holding case is shown to have end walls 4, with right-angularly bent flanges 4', to serve as the front and rear walls of the 50 case. As shown in Figure 1, the front and

rear of the case is open so that contents of the case and the front and rear thereof are substantially entirely exposed. The walls 4 are joined by an integral bottom member 5, having right-angularly upturned flanges 5', 55 which assist in properly holding a package in the case, the walls and bottom being formed by bending a single strip of material.

The flanges 4' are enlarged at 6 near the upper portion of the case, and the part 6 is 60 cut and bent over to provide bearings 7, 8, 9 and 10 for a pivot pin.

The vertical front side portion of a cover 12 also has portions 13, 14 and 15 cut and bent to provide bearings for the pivot pin 16, the 65 latter passing through all of the bearings described above. Encircling the pin 16 between the bearings 8 and 13, is a coiled spring 17, one extremity 18 of which engages the inner surface of cover wall 11, while the 70 other extremity 19 engages the flange portion 6, the effect of the spring being to normally move the cover to an open position as shown in Figure 3.

The end vertical wall 20 of the cover 12 75 is provided with a slot 21 which cooperates with a lug 22 to hold the cover in a closed position.

It will be seen that the cover 12 extends only one half of the upper portion of the 80 case. The other half of the case is covered by a cover 23 which is of a structure similar in all respects to cover 12.

A flat spring 24 is secured to the end wall 4 by means of a rivet 25, the lugs 22 being 85 formed integral with the upper extremity of the flat spring 24. Slightly below the covers 12 and 23, the spring is provided with a button 26 which extends through an aperture in wall 4.

In operation, a paper package 27 of cigarettes is placed in the case as shown in the drawings, the top of the paper package being torn off. The covers 12 and 23 are then 95 moved to the positions shown in Figure 1, and held in a closed condition by means of the lugs 22 on spring 24 engaging the slots 21.

When it is desired to open the case, pressure on button 26 will move the spring back- 100

wards to disengage the lugs 22, and the coil springs 17 will cause the covers 12 and 23 to automatically open.

The case herein described properly protects the cigarettes from damage, the arrangement of the covers enables access to the cigarettes 28, regardless of their position in the paper package 27.

The foregoing disclosure is to be regarded as descriptive and illustrative only, and not as restrictive or limitative of the invention, of which, obviously, an embodiment may be constructed including modifications without departing from the general scope herein indicated and denoted in the appended claims.

Having thus described my invention, what I claim as new and desire to secure by Letters Patent, is:

1. A cigarette package holding case, comprising end walls and a bottom, right-angularly in-turned flanges integral with said walls and bottom, a two-part cover opening longitudinally of the mouth of the case, means for hingedly connecting the parts of the cover to the free ends of the end wall flanges, spring controlled means for holding the cover in a closed position, and means to normally urge the parts of the cover to open outwardly, said cover being parallel to the bottom when in a closed position.

2. A cigarette package holding case, comprising end walls and a bottom, right angularly inturned flanges integral with said walls and bottom, a two-part cover opening longitudinally of the mouth of the case, and means for hingedly connecting the parts of the cover to the free ends of the end wall flanges.

This specification signed this 23rd day of September, 1929.

WILLIAM C. HIERING.
